UNITED STATES PATENT OFFICE.

ALTER L. SCHWARTZBERG, OF SHREVEPORT, LOUISIANA.

DESIGN FOR A BAR OF SOAP.

51,395.

Specification for Design.

Patented Oct. 16, 1917.

Application filed August 10, 1917. Serial No. 185,613. Term of patent 3½ years.

To all whom it may concern:

Be it known that I, ALTER L. SCHWARTZBERG, a citizen of the United States, residing at Shreveport, in the parish of Caddo and State of Louisiana, have invented a new, original, and ornamental Design for a Bar of Soap, of which the following is a specification, reference being had to the accompanying drawing, forming part thereof.

Fig. 2 is a side view thereof.

I claim:

The ornamental design for a bar of soap, as shown.

ALTER L. SCHWARTZBERG.

Witnesses:

SAM WARE,
FRANK GORDON.
